UNITED STATES PATENT OFFICE.

HERBERT J. LEIGHTON, OF SYRACUSE, NEW YORK.

FORCE-FEED LUBRICATOR.

1,243,309.

Specification of Letters Patent. Patented Oct. 16, 1917.

Application filed December 7, 1916. Serial No. 135,635.

To all whom it may concern:

Be it known that I, HERBERT J. LEIGHTON, a citizen of the United States, and a resident of Syracuse, in the county of Onondaga and State of New York, have invented a certain new and useful Force-Feed Lubricator, of which the following is a specification.

This invention relates to force feed lubricators particularly adapted for motor vehicles or any other machines in which a lubricant is fed to a plurality of points, and has for its object a construction whereby the outlet passages of the lubricator are provided in a very simple and economical manner. The invention consists in the combinations and constructions hereinafter set forth and claimed.

In describing this invention, reference is had to the accompanying drawings in which like characters designate corresponding parts in all the views.

Figure 1 is a plan view of a lubricator embodying my invention, the container for the oil being removed and the driving shaft being shown in section.

Fig. 2 is a plan view of the base and plate thereon which forms the cover for the grooves therein, the plate being partly broken away.

Fig. 3 is a sectional view, partly in elevation, on the plane of line A—A, Fig. 1.

Fig. 4 is an inverted plan view of the pump, a portion of its casing being broken away.

Fig. 5 is a fragmentary sectional view taken on line A—A, Fig. 1.

This lubricator comprises generally, a body including two parts, one a base and the other a member or plate lying on the base, one of said parts, here shown as the base, being formed with grooves in the face thereof opposed to the other part, so that the latter covers the grooves, and one of said parts, here shown as the plate, being formed with perforations registering with portions of the grooves and forming ports through which the oil enters the grooves, and a pump for forcing the oil through said perforations and the grooves.

1 designates the base which is formed with a flat face having a plurality of grooves 2 including portions 3 which extend in radial directions from the inner ends of the grooves, and outer portions which com-

municate with outlet ports 4, said inner ends 55 of the grooves being illustrated as arranged in a circular series.

5 is the plate mounted on the base and serving as a cover for the grooves 2, the plate having a circular series of perforations 6, which register with the inner ends 55 of the radial portions 3 of the grooves 2 and constitute ports through which the oil enters the grooves 2.

7 designates the pump casing, mounted 65 on the plate 5 and secured in position in any suitable manner as by fastening members 8 passing vertically through a base flange 9 on the pump casing and through openings 10 in the plate and alined openings 70 11 in the base 1.

The movable parts of the pump in this form of my invention, include a pair of intermeshing gears 12, 13 engaging, on like sides as their lower sides, with the plate 5, 75 the gear 13 being connected in any suitable manner to a driving shaft by a shaft section 14 journaled in a vertical bearing 15 in the casing 7, the shaft section having means at its upper end for connection to the driv- 80 ing shaft.

The gear 13 is formed with a transverse delivery passage 16 therethrough arranged to come successively into alinement with the perforations 6, in order to deliver the lubri- 85 cant successively to the perforations 6, so that individual impulses are imparted to the oil in the grooves 2.

The gear 13 is provided on its upper face with an annular groove 17 into which 90 grooves 17 the delivery passage 16 opens. The entrance for the lubricant into the casing 7 is located at 18 an one side of the point at which the gears mesh and the compression chamber 19 is located on the other 95 side of said point, the casing being formed with a connection between the chamber 19 and the groove 17.

20 is the wall of a container mounted on the base and held in position by fastening 100 members extending through alined openings 21, 22 and 23 in the container, the plate 5 and the base 1. The container is usually bolted to the crank casing of the engine and is in communication with the 10 crank casing in order to receive oil therefrom, the oil entering the container through the opening in the top of the container.

The ports 4 are preferably arranged in one side edge of the base, and pipes lead therefrom to the points to be lubricated.

Owing to the base 1 with the grooves 5 therein and the plate 5 covering the grooves and having ports opening into the grooves, expensive machining and boring of the base is eliminated, and the base 1 can be die cast of a comparatively soft metal with 10 the grooves therein and the plate 5 formed of a harder metal as brass capable of standing the wear of the movable parts of the pump.

What I claim is:

15 1. A force feed lubricator comprising a body including a base formed with grooves in one face thereof, a plate mounted on the base and covering the grooves and formed with perforations communicating with portions of the grooves and constituting ports therefor, a pump casing mounted on the plate and movable parts within the casing for forcing the oil into the grooves through the ports, said movable parts engaging the 25 plate, substantially as and for the purpose specified.

2. A force feed lubricator comprising a body including a base formed with grooves in one face thereof, a plate overlying said 30 base and covering the grooves, the plate being formed with a series of perforations arranged to come into alinement respectively with portions of said grooves and constituting ports, a pump casing mounted 35 above the plate, and movable parts located in the casing and including a distributor having a delivery passage arranged to come successively into alinement with said ports, substantially as and for the purpose set 40 forth.

3. A force feed lubricator comprising a body including a base formed with a series of grooves in one face thereof, the inner ends of which grooves are arranged in a 45 circular series, a plate overlying the base and covering the grooves, the plate being formed with perforations in alinement with the inner ends of the grooves, the perforations constituting a circular series of inlet 50 ports for the grooves, a container mounted above the base and the plate, and a pump mounted on the plate within the container for forcing oil through the perforations, substantially as and for the purpose de- 55 scribed.

4. A force feed lubricator comprising a body including a base formed with grooves in one face thereof and with a series of outlet ports, the grooves communicating with 60 the ports, a plate mounted on the base and covering the grooves and having ports for

registering with inner end portions of the grooves, and a pump for forcing oil through the ports at the inner ends of the grooves to the outlet ports, substantially as and for 65 the purpose specified.

5. A force feed lubricator comprising a body including a base formed with grooves in one face thereof, and a series of ports, the inner ends of the grooves terminating in 70 a circular series, and the grooves communicating at their outer ends with the outlet ports, a plate mounted on the base and forming a cover for the grooves, the plate being formed with a circular series of perforations aligned with the inner ends of the grooves, a pump casing mounted on the plate, and movable parts located in the casing and including a rotary distributor engaging the plate and having a delivery passage arranged to come successively into alinement with the perforations of the plate, substantially as and for the purpose set forth. 75

6. A force feed lubricator comprising a 80 body including two parts, one a base and the other a plate lying on the base, one of said parts being formed with grooves in the face thereof opposed to the other of said parts, and one of said parts being formed 85 with perforations opening into the grooves, and means for forcing the oil through the perforations and into the grooves, substantially as and for the purpose specified. 90

7. A force feed lubricator comprising a 95 body including two parts, one a base and the other a plate lying on the base, one of said parts being formed with grooves in the face thereof opposed to the other of said parts, and the plate being formed with 100 perforations opening into the grooves, and a pump mounted on the plate and including a movable part for forcing the oil through the perforations, said movable part engaging the plate, substantially as and for 105 the purpose set forth.

8. A force feed lubricator comprising a body including two parts, one a base and the other a plate lying on the base, one of said parts being formed with grooves in 110 the face thereof opposed to the other of said parts, and the plate being formed with a circular series of perforations opening into the grooves respectively, and a pump mounted on the plate for forcing oil through 115 the perforations, substantially as and for the purpose specified.

In testimony whereof, I have hereunto signed my name, at Syracuse, in the county of Onondaga, and State of New York, this 120 5th day of December, 1916.

HERBERT J. LEIGHTON.
